UNITED STATES PATENT OFFICE

2,003,220

TYPE-SETTING DEVICE

William J. Pearson, Los Angeles, Calif.

Application October 23, 1931, Serial No. 570,632

16 Claims. (Cl. 101—93)

This invention relates to improvements in type-setting devices for parcel post machines and the like, such as is disclosed in my co-pending application, Serial No. 367,106, filed May 29, 5 1929, entitled Parcel post weighing and stamp printing machine, by William J. Pearson, designed for weighing parcel post packages and the like, and for printing metered prepaid stamps for the same.

10 The parcel post weighing and stamp printing machine, disclosed in said application, is designed for printing purposes, more particularly the printing of metered parcel post stamps wherein it may be required to print a stamp 10 bearing the name of the place of original mailing, the date, the zone number to which the package is addressed, the weight of the package, the monetary value of the stamp derived from the weight and the zone, a serial number, 15 and such other words, phrases, figures, decorations and designations as it may be desired to print. This mechanism is used in conjunction with a scale, meters, printing mechanism, and a paper supply, and may be motor driven and 20 used for any printing purpose.

This mechanism is particularly adapted for the printing of parcel post stamps upon a paper strip which is fed through the machine and when printed is cut to the proper stamp length, and being gummed on the reverse side may be moistened at the delivery point of the machine and in this condition attached to the package 25 to be mailed.

This mechanism is also designed to be used 30 in conjunction with a metering or registering device which continuously registers within a set of numeral wheels constituting the meter, the monetary values of the stamps printed; and also with a control meter which may be set for a 35 predetermined monetary value, and which, upon exhaustion of that amount, will function to lock the entire machine against operation until again so set, and may be so disposed as to actuate any other mechanism that may be desired.

40 This invention provides a novel method of setting up within the machine the mechanical equivalents of numbers put in the machine by an operator by actuation of the keys of a keyboard.

45 More particularly, the invention provides a novel method of setting up a series of type within the machine through the use by an operator of a single bank of ten keys, which, when the required numbers have been set up or the 50 required number of keys operated on the keyboard, may be operated by means of a control key and the connected motor drive, perform the printing operation, whereupon the entire machine is cleared and re-set preparatory to the 55 next setting and printing operation.

In the form of the machine disclosed there are six numbers to be printed, hence six figures must be set up in the machine; therefore, six keys on the keyboard must be punched or six key-actuations must be performed before the 5 progressive release lock will be fully operated to unlock and allow the printing mechanism to function; it is impossible to print a stamp until the required number of keys have been punched on the keyboard, thus reducing to a minimum 10 the possibility of printing incorrect or mutilated stamps and the consequent registering of incorrect amounts within the meters.

This invention includes a printing mechanism comprising multiple type adapted to be set up 15 by a single keyboard of ten keys successively for printing purposes, which type may be returned to their original zero positions at the will of the operator, and which will be automatically returned to original position at the 20 completion of a printing operation.

An object of my invention is to provide in a parcel post machine means for setting up combinations of figures by means of type wheels within the numeral printer, a keyboard of a 25 single bank of ten keys being employed to progressively set up the type.

An object of my invention is to provide a printing mechanism comprising a series of printing wheels actuated by a keyboard mechanism 30 and rotated to a position corresponding to the numbers put into the keyboard, successively and in order, and presenting the selected type faces in printing relation to a platen.

An object of my invention is to provide a 35 printing mechanism comprising a locking element adapted to engage the printing wheels while still in geared relation to the setting means, and retaining them in locked position during a printing operation, returning them to 40 the same geared relation to the setting means which they occupied before the locking operation occurred.

An object of my invention is to provide a 45 printing mechanism comprising a platen against which the type operate to print, which includes a duplicating mechanism composed of an inked ribbon and spools for winding the ribbon, re-winding mechanism and reversing mechanism for the ribbon, and runways or guides for the 50 paper strips to pass through under the printer, the ribbon lying between the two paper strips and allowing the type to print a duplicate stamp by the force of the blow delivered against the platen.

An object of my invention is to provide a 55 printing mechanism, including a drive mechanism, wherein the motive power is continuously supplied during the entire printing cycle of a machine, but intermittently connected to the 60

printer parts, for actuation only at selected points in the cycle of operation, relative to the operation of other operative parts of the machine. For this purpose I have provided a novel 5 clutch mechanism which intermittently engages and disengages the drive elements with the driven elements.

An object of my invention includes a novel 10 method of operation of a machine from a keyboard comprising ten keys from 0 to 9 inclusive, a control key for the operation of the clutch of the power drive, and an error key for manually initiating the clearing operation of the machine. I have provided mechanism whereby the 15 numbers punched in on the keyboard will be successively transmitted by mechanical movement to the printing and meter-actuating elements, thus providing a means to set up six different figures with the use of only a single 20 bank of ten keys.

An object of my invention is to provide a keyboard of the simplest form and character to provide ease and simplicity of operation for an operator of an otherwise complicated machine, 25 and to provide mechanism that will respond to a very light touch upon the keys. To that end I have provided a series of power driven clutches disposed between the keys and the machine actuating elements, hereinafter called the key bars; 30 each key is essentially a clutch actuating lever by which the power is connected from its source to the machine operating elements.

An object of my invention is to provide a 35 mechanism whereby a multiple of numbers may be set up in a machine by means of a type-setting device comprising a keyboard with a single bank of ten keys, this multiple of numbers being operated successively and in the order which they will assume when printed, an extension of the same mechanism also transferring the mechanical equivalents of the same numbers to meter-actuating mechanism which is operated to actuate a permanent total meter and a downward count meter hereinafter termed 40 the control meter; the meters are actuated to register the number at the time that the printing operation takes place in the machine; at the completion of the printing operation the machine is cleared of the numeral set-up, and such parts 45 as need to be set for operation are re-set in a position necessary for such operation.

This type-setting device also includes selector 50 elements which transmit the movement originating at the keyboard to the numeral printer and the meter set-up mechanism by successive positions and contacts, making one longitudinal movement upon the operation of a key in the keyboard and subsequently making an escape- 55 ment movement transversely of the original movement, thereby positioning the contacting member in preparation for the actuation of the next type member by the next operation of a key of the keyboard.

This device also actuates a progressive release 60 lock which is set at an original position so that it may be rotated one step for each key operated on the keyboard until the number of keys corresponding to the number of digits of the number to be printed have been operated, which, 65 in the machine disclosed, is six; thereupon the locking element adjacent the power clutch is released, and the machine may be operated for printing purposes; but should any number of keys other than the six required be operated, it 70 will be impossible to engage the clutch for print-

ing purposes, since the lock will not have been released; the machine must then be cleared and the numerals must be correctly punched into the machine by means of the keyboard before the machine can be operated.

Another object of my invention is to provide a keyboard mechanism wherein certain keys controlling operations of the machine, i. e. the error key and the control key, may be operated independently of each other, but when one is operated the other is locked against operation, thus providing a safety measure in the operation of the machine.

Another object of my invention is to provide a clutch element between each of the keys and the respective key bar; to that end I have provided a type of clutch connection through which instant operation occurs at the touch of a key, and which is simple in construction and durable; also I have provided a power return for each 20 key depressed, automatically releasing each clutch upon one revolution, thus preventing more than one impulse being transmitted from the keyboard from one depression of a key.

Various other objects and advantages will be more fully apparent from the following description of the accompanying drawings which form a part of this disclosure, and which illustrate a preferred form of embodiment of the invention.

Of the drawings:

Fig. 1 is a plan view of a portion of a parcel post machine comprising the front right section of the machine, with the casing broken away to disclose the interior mechanism.

Fig. 2 is a plan view of a portion of the machine showing the front left section, with the casing broken away, this view, together with Fig. 1, disclosing the entire front section of the machine in plan.

Fig. 3 is a vertical sectional view taken on line 3—3, of Fig. 1.

Fig. 4 is an enlarged vertical sectional view taken approximately on line 4—4 of Fig. 1.

Fig. 5 is a vertical sectional view taken approximately on line 5—5 of Fig. 1, but omitting the selector and its connected mechanism; this figure is for the purpose of showing the meter control lock mechanism.

Fig. 6 is an enlarged vertical sectional view taken approximately on line 6—6 of Fig. 1, and 50 illustrates the selector and elevator mechanisms and their connections.

Fig. 7 is an enlarged sectional view, showing the keyboard and one of its clutches in section and their relation to the selector, and taken approximately on the line 7—7 of Fig. 1.

Fig. 8 is a detail sectional view of the elements of the keyboard clutch shown in Fig. 7.

Fig. 9 is a transverse vertical sectional view taken approximately on line 9—9 of Fig. 1, and 60 line 9—9 of Fig. 2, showing the relation between the key bars, the selector and the numeral printer.

Fig. 10 is a detail sectional view of the numeral printer showing the elements thereof in 65 printing position.

Fig. 11 is an enlarged transverse sectional view, showing the relation of the key bars and 70 one of their connections to the selector, and taken approximately on line 9—9 of Fig. 1.

Fig. 12 is a semi-diagrammatic view of the selector from the front in elevation and partly in section, the solid lines representing the normal position of the elements and the broken lines their extreme longitudinal movement.

Fig. 13 is a semi-diagrammatic view of the selector in elevation and partly in section, taken approximately on line 13—13 of Fig. 12, the original position being shown by the solid lines 5 and the extreme lateral movement by the broken lines.

Fig. 14 is a semi-diagrammatic plan view of the selector, the bank of push bars and the contacting ends of the rack bars wherein is 10 shown in solid lines the original position of these various elements and in broken lines one position assumed by the selector upon actuation of the lowest numeral key in the keyboard.

Fig. 15 is a semi-diagrammatic plan view 15 similar to Fig. 14 showing the selector in solid lines in the position it will have assumed after three keys have been actuated in the keyboard and wherein it is now positioned for actuation by a fourth key; the broken lines herein 20 represent the position the selector would assume should the key on the keyboard numbered 5 be depressed, thus illustrating the amount of movement required to transmit the key action from key 5.

Fig. 16 is a semi-diagrammatic plan view 25 similar to Figs. 14 and 15, wherein the selector is shown at its extreme limit of movement in one direction, namely, wherein five keys have been depressed upon a keyboard; the selector 30 is now in position to operate upon the depression of the sixth key; the broken lines herein represent the extreme movement upon actuation of the ninth key on the keyboard, which creates the greatest longitudinal movement of 35 these members.

Fig. 17 is an enlarged transverse vertical sectional view, similar to the left-hand portion of Fig. 9, showing the selector and the numeral printer and their component parts and showing 40 in diagrammatic form the various actuating members for the numeral printer, certain parts being omitted to disclose parts otherwise hidden.

Referring to Figs. 1 and 2, the keyboard A is 45 the origin of movement in a setting-up operation; by means of the key bars B movement originating in the keyboard is transmitted to several elements operated therefrom, among which is the selector C, which progressively transmits movement originating in the keyboard A by a step by step process, contacting progressively each of the sets of rack bars D which are a part of the numeral printer E (Fig. 2). The setting up operation is carried 50 by means of the connections F (Fig. 1) to the meter set-up mechanism G and the numeral indicator H.

For the printing operation there is provided 55 a source of motive power, (not shown), which is connected to the driven mechanism by means of the shafting J, to which is connected the clutch K lying intermediate of the driving and driven members and controlled from the keyboard A; this clutch shafting J drives the driven elements of the machine by means of the connected drive gearing L, (Figs. 1 and 2) which drives the numeral printer E and the rotary printer M by means of the intermediate clutch and its connected gearing N; also connected to 60 the drive element L is a drive element O (Figs. 1 and 2), where it is related to certain portions of the meter-actuating mechanism G, by means of which the operation of the machine for printing purposes actuates the meter-actuating mechanism G to transmit into the control meter 65

P, (Fig. 1) and the total meter R (Fig. 2), the numbers set up.

For controlling the operations of the machine for printing purposes and securing accuracy in the setting up operation, I have provided a progressive release lock S (Fig. 1); for the purpose of clearing the machine, both by manual operation originating at the keyboard and automatically by means of the drive element L, I have provided a clearing mechanism centering principally around shaft T (Figs. 1 and 2). 5

For the purpose of receiving a printed stamp at the completion of the printing operation and for moistening and delivering the same, I have provided the moistening unit U (Fig. 2). For 15 the purpose of providing means to lock the machine against operation upon exhaustion of a pre-set amount of postage set in the control meter P, I have provided a meter-controlled locking mechanism V (Figs. 1 and 2), the motor 20 circuit being broken by the locking operation; also the main drive element L is mechanically locked against rotation in one direction, and to prevent its operation at any time in an opposite direction, I have provided a non-reverse element W (Fig. 2). 25

The keyboard A, in which originates movement in the operation of a set-up of numerical figures in the machine, comprises a set of ten keys 23, (whereby six different figures are set 30 up within the machine), an error key 21 (by which the clearing operation of the machine is actuated) and a control key 22 (whereby the power clutch K is actuated). The keyboard A is provided with a set of clutches 23, (one of 35 which is disclosed in Fig. 7); the driving element J (Fig. 1) is continued to a point adjacent the keyboard A, and the connecting gearing 24 is connected to a main clutch shaft 25 (Figs. 3 and 7), which has secured to it a toothed ele- 40 ment 26.

Rotatively mounted on the shaft 25 adjacent to the toothed element 26 is the cam element 31, which has secured to it the eccentric element 27, (shown by broken lines in Fig. 8); this eccentric 45 27 carries an eccentric ring 28 (also shown by broken lines in Fig. 8); the eccentric ring has an elongated connection 29 by means of which it is connected to a rocking member 30, which in turn is connected to one of the key bars of the key bar bank E.

The keys 26 and their connected key stems 31 are virtually clutch-engaging levers; upon depression of the key 26, the key stem 31 rocks the trip lever 32, whereupon the trip 33 is disengaged from the latch 34 (the unlatched position being shown in Fig. 8); the latching member 35 is pivoted at 36 to the cam member 37, which is secured to the shaft 25; upon release 55 of the latch 34 by the trip 33, the latch member 35, tensioned by spring 38, is moved (as shown in Fig. 3) a sufficient distance to bring the latch tooth 39 into the path of one of the teeth of the toothed member 26; the engagement of these parts (Fig. 8) causes the cam member 37, and consequently the eccentric 27 to rotate; this rotation causes the extension member 29 to oscillate in a vertical plane and transmit movement to the link 30 and the particular key bar connected thereto. 70

The rotation of the cam member 37, which is provided on its periphery with a cam face 40 including the dwell 41, upon the engaging of the clutch and the consequent rotation of the parts thereof, causes the cam slide 42 to move out of 75

the dwell 41 and ride upon the peripheral face of the cam; this movement of the cam slide 42 (which is incorporated in one end of a rocking arm 43) causes the opposite end of the arm 43 5 to actuate and engage bell crank lever 44, which in turn engages each of the series of trip levers 32 and raises them, together with the key stems 31 and the keys 28, to their original position.

This rocking of the trip levers 32 again places 10 the trip 33 in the path of the latch 34, so that, upon one complete rotation of the latch 34 in engagement with the clutch element 26, the latch again arrives at the contact point with trip 33; this contact causes the tooth 38 to be disengaged 15 or removed from the path of the contacting tooth on the tooth member 28, thus releasing the driving and driven members of the clutch from engagement; an additional function of the elements 43 and 44 is to lock all of the key stems 20 31 against depression during a rotation of the clutch.

Movement inaugurated in the keyboard is thus transmitted, by means of the link 39, to a key bar 45, (Fig. 7); the key bar 45, being fulcrumed at one end, is depressed by the link 39, which is fulcrumed on an adjustable fulcrum stand 46; the key bar 45 has attached to it one of a series of differential bell cranks 47 by means of which, together with the slide bars 48 30 connected thereto, movement is transmitted to the selector. Upon depression of one of the keys in the keyboard A a corresponding slide member 48 is moved a distance corresponding to the key depression; each of the bell crank levers 35 47 is so proportioned and arranged as to transmit a movement in accordance with the particular number represented by the key to which it is connected each of the different bell cranks moves a definite distance farther than the next 40 preceding one, thereby providing a series of movements for actuating the selector different distances for each of the different keys of the keyboard.

The selector C is composed of a frame 49 45 provided with bearing rollers 50 which support a carriage 51 provided with tracks 52 for engagement with the bearings 50, and having a longitudinal movement thereon when actuated by the slide members 48; the carriage 51 is provided with a track 53 in which slides the selector slide member 54; this slide 54 moves transversely to the movement of the carriage 51, and is tensioned for this lateral escapement travel by a tension spring 56, secured at one end to 50 a post 55 on the carriage, the other end being secured to a convenient part of the machine; the carriage 51 also has secured to its upper edge an actuating member, namely, the selector arm 57, which is so disposed that, in its step by step 55 escapement travel, it will contact successively each of the rack bar members D of the numeral printer E.

The slide member 54 is provided on its lower face with a set of escapement teeth 58 which 60 contact a spring tensioned pawl 59; upon the longitudinal movement of the carriage 51 the tooth presented to the pawl will be moved out of engagement with the pawl 59 and along a guide plate 60, at which time the pawl 59, having thus been released, will be moved to one side (to the right in Fig. 7) by its spring 59a; the pawl is limited in its movement to the distance of one tooth by stop 59b, so that it will be just 65 out of the path of the tooth presented upon the 70 return of slide 54 to the original position, and,

therefore, the slide 54 under the influence of spring 56 will move laterally (to the left in Fig. 7) until the next succeeding tooth 58 is engaged by the pawl 59 and is stopped when it has moved the distance of one tooth by engagement of pawl 59 with its stop 59c, in which position the selector arm 57 will be aligned with the next succeeding rack bar D. This escapement operation occurs at each travel of the carriage 51, thereby presenting the selector arm 57 10 successively to each of the rack bars D.

This successive step by step movement of slide 54 and selector arm 57 of selector C is shown and described in copending application of George W. Lawrence, filed October 23, 1931, 15 Serial Number 570,634.

The sequence of movement from the keyboard A having been described as to the rack bars D (Fig. 2), I will now describe the numeral printer E in which the rack bars D are situated. 20

The numeral printer E (Figs. 9, 10 and 17) comprises a printer for the purpose of printing numerals upon a stamp, a removable dater block 61, a series of rotatable type wheels operated to a set-up position by the rack bars D, 25 and an automatic serial numbering device (not shown) adjacent thereto, actuated to increase one unit for each of the printing operations and provided with type faces similar to and in alignment with those on the numeral wheel 62; the 30 numeral wheels and the numbering device are rotatively assembled on the shaft 63, which is secured at either end into an assembly comprising the slides 64 and the cross connection retaining plate 65.

For the purpose of creating the required hammer-like blow for printing there is provided a hammer 66 tensioned by means of springs 67 and having a type locking portion 68 adapted to engage the presented tooth-shaped type face 40 of the numeral wheels 62; the hammer 66 is rockably connected to the arms 69 by means of a connecting pin 70 (Fig. 17); the arms 69 are secured to rocking shaft 71 mounted at each end in the supporting side plates 72 of the printer 45 and extending at one end a sufficient distance to have secured thereon a member 73 (Fig. 2), which is tensioned by means of the spring 74 for the purpose of making the hammer blow.

For the purpose of operating the numeral 50 printer E and its various connections the drive element L is gear-related thereto by means of a gear 75 and a driven gear 76 on shaft 77; the shaft 77 has mounted thereon a grooved cam 78 in which operates a cam roller, (not shown), 55 secured to the member 73; upon the occurrence of the printing operation, the member 73, with its roller, is so disposed to the cam groove that there is presented a clear path in the groove of sufficient distance to provide for the spring 74 60 to operate the printer mechanism for making a print; subsequently, the cam 78, continuing to rotate, rocks the member 73 and returns the engaging members of the printer to their original position, as shown in Fig. 17.

Several elements within the numeral printer E carry on various functions, such as the inking of the type, and the actuation of the serial numbering device and the return of the rack bars; for these purposes I have provided a series 70 of cams secured to the shaft 77; the cam 79 (Fig. 17), for actuating the serial numbering device, is located on the shaft 77 and contacts a member 80 which is connected to perform this function; cam 81 on the shaft 77 functions to oper- 75

ate the inking device; this cam 81 has a dwell 82 into which the spring-tensioned member 83 drops upon the rotation thereof; by multiplying levers this movement is increased so that the inking roller 84 travels the length of the track 85, passing across the face of the ink pad 86, and contacting the type faces of the type in the numeral printer; as the cam 81 rotates the dwell 82, the contact member 83 rides out to the periphery of cam 81 and is actuated to return to normal position, thus returning the ink roller 84 to its original position.

After the completion of a printing operation the clearing action takes place; for power return of the rack members D during the clearing action I have provided a contacting bar 87 mounted in arms 88 which are pivoted on the shaft 89 and actuated by means of the connecting lever 90 and a rocking member 91 which contacts a cam 92 secured to the shaft 77; at the proper point of the rotation of the shaft 77, cam 92 operates rocking member 91, to rock the bar 87, through connecting lever 90. When thus rocked (to the right in Fig. 17) bar 87 engages and moves the rack bar extensions 108 to return the rack bars D to their original position.

The rack bars D are provided with a rack face 93 (Fig. 17) which contacts pinions 94; upon the longitudinal movement of the rack bars D, the pinions 94, which are secured respectively to each of the numeral wheels 62, thereby rotate each numeral wheel 62 to bring to the printing position the type corresponding to the key depressed in the keyboard A.

For maintaining the rack bars D in the set-up position until after a printing operation, I have provided pawls 95, which are rockably mounted on a spring-tensioned slideable shaft 96 (Fig. 2), which is operated during the clearing action to slide the pawls 95 sideways and disengage them from the particular teeth of the ratchet teeth 97 being contacted, thus releasing the rack bars D to return to normal position; the teeth 97 are spaced in accordance with the degree of movement necessary to rotate the type faces of the numeral wheel 62; and the spacing of the teeth provides, by movement for the distance from one tooth to the next succeeding tooth, for corresponding movement necessary to move one type face past the printing zone and bring the next type face into printing position.

In order that a duplicate stamp may be made, I have provided an ink ribbon device (Fig. 9) in which the ink ribbon 98 is wound alternately upon one or the other of two spindles 99, by means of a winding and reversing device 103 (Fig. 2) when either of the spindles 99 has approximately the entire length of the ink ribbon wound thereon, the other end of the ink ribbon being firmly secured to the other spindle, the pressure of resistance created by the ribbon when it stops throws over the reversing mechanism, and the ink ribbon is then wound upon the opposite spindle; upon its being fully wound upon this spindle the operation occurs again for reversing to the other spindle, and so on indefinitely, thus providing a means for automatically winding and reversing the ink ribbon.

To provide for a platen against which the numeral printer will act, I have provided the anvil 102 in-set with a semi-resilient material 101, and having a guide plate 103 for separating the paper tapes one from the other, and allowing the ink ribbon to repose therebetween, for

the purpose of printing a duplicate stamp; these members are mounted upon plates (not shown) at either end of the device.

The operations of the numeral printer E are apparent from Figs. 9, 10, and 17. Figs. 9 and 17 show the numeral printer in normal position. Fig. 10 shows the printer in printing position, when the hammer 66 has descended; the engaging portion 68 of the hammer 66 has engaged the presented tooth portion of a numeral wheel 62, restraining it from rotary movement upon the shaft 63, and the pinion 94 has been disengaged from the rack 93. The return movement of the hammer 66, by means of the springs 67, first raises the top plate 65, which, by its connected portions supports the various members of the numeral printer; upon the plate 65 being returned to contact with the top of the printing frame 72, the hammer continues to rise against the springs 67 until the engaging portion 68 is raised clear of the numeral wheel 62 and the pinions 94 again engage the racks 93 in the same gear relation they occupied prior to the printing operation.

I will now describe the transference to the meter set-up mechanism of the set-up movement, which is effected prior to a printing operation, which mechanism, upon a printing operation taking place, is actuated to transmit into the two meters the mechanical equivalent set up within the set-up mechanism, by actuation of the keys of the keyboard A.

Only the combination of figures representing the monetary value of a stamp are registered on the meters herein; consequently, in the particular machine illustrated, only three figures are conveyed and only three rack bars of the rack bar unit D are involved in this operation, these being the rack bars 105, 106 and 107; the rack bar 105 represents the dollars, rack bar 106 represents the tens of cents, and rack bar 107 represents the cents units (Fig. 2); the connecting bars 108, 109 and 110, being connected to the rack bars 105, 106 and 107, transmit the movement during a set-up operation to gearing 111 from which the movement is transmitted to the meter set-up mechanism F by means of the gearing 112 (Figs. 1, 4, 5 and 9).

The meter set-up mechanism F comprises three units, (Fig. 1), including the three elevators 113, 114 and 115 gear-related to the meters.

Gearing 112 has pinions 116 which engage with a rack member 117 slidably attached to a carriage 118, which carries the elevators 113, 114 and 115, each provided with steps 119 so designed as to correspond with the ratchet teeth 97 of the rack members D; each of the steps represents and is the mechanical equivalent of one of the numbered keys on the keyboard A, and the rotation of the gearing 112 by actuation of a key moves one of the elevators laterally on its carriage 118 a distance corresponding to the particular key actuated on the keyboard; this movement of the elevator selectively and differentially positions a corresponding step 119 to engage and actuate the movement forwarding mechanism comprising rack bar 125; the actuating operation occurs during the printing operation; a shaft 121 beneath the elevators, geared to secondary drive shaft 120, has secured to it three cams 122, 123 and 124; these cams operate to raise the elevators 113, 114 and 115 and their associated rack bars 125 in succession for

the purpose of presenting only one of the numerals at a time to the meters.

In view of the fact that this machine handles numerals with monetary values, the meter must act to provide for the carry-over from one numeral wheel to the other, independently of the drive mechanism; it is for this purpose that the drive mechanism presents the numbers to the meters in a regular sequence.

- 10 The operation of the cams 122, 123 and 124 raises the elevators 113, 114 and 115 in succession; the raising of the elevators brings the steps previously positioned into contact with the respective rack bars 125 raising each rack bar a distance equivalent to the number being transmitted; the rack bar, meshing with the pinion 126, rotates the pinion to such an extent as to transmit the mechanical equivalent of the number to the connected numeral wheel of the meter. This progression of movement from the elevators to the meters is continued through shafts 127 and 128, which deliver the proper movement to both the control meter P and the total meter R.
- 25 The first three meter wheels in each of these meters are provided with internal ratchet teeth (not shown), thus providing for the drive operation and the return of the selectors to their original position.
- 30 To insure the proper and positive return of the meter-actuating selectors (pinions 126 and racks 125) to their original positions, I have provided a power driven return device comprising a cam 129 mounted on the secondary drive shaft 120, which cam 129 contacts and operates a cam roller 130 mounted on a rock shaft 131 (Fig. 4); secured to this shaft 131 are rock arms 132 which contact the tops of the racks 125; upon the rotation of the cam 129, the arms 132 force the racks 125 downwardly, rotating the pinions 126 to the original starting point.

For visual indication of the monetary amount set up in the numeral printer and in the meter set-up mechanism, I have provided an indicator H (Fig. 6), directly connected to the gearing 112 by engagement of a double rack bar 133 with pinions 134 attached to the visual numeral wheels 135; these numeral wheels are operated with the set-up mechanism and are also returned to the zero position upon the return of the set-up mechanism to its original position, either at the close of a printing operation, or when cleared manually by means of the error key 21 of the keyboard A.

The operation of clearing the machine, automatically at the completion of a printing operation or manually by the operation of error key 21, comprises rocking the rock shaft mechanism T, which includes a main rock shaft 136 and a cam rock shaft 137 (Figs. 1 and 2).

The rock shaft 137 has mounted on it a cam roller arm 139 and a cam roller 138, actuated by a cam 140 secured to the drive shaft L; the rock shaft 137 also has secured to it a cam member 141 adapted to contact and axially move the spring-tensioned slide shaft 96 on which are secured the pawls 95 which engage and hold the various rack bars D, when thus moved by the cam 141 the slide shaft 96 disengages the pawls 95 from the ratchet teeth 97, allowing the rack bars D to return to original position. The rock shaft 137 has secured to it a rocker arm 142 which, by means of a link 143, is attached to a similar member 148 on rock shaft 136, thereby rocking

this shaft in unison with the rock shaft 137 (Figs. 2 and 4).

Attached to the rock shaft 136 is a rock arm 144 connected to a rack bar 145 adapted to actuate the progressive release lock S to return it to normal position.

The rock shaft 136 also has attached to it the arm 146 (Fig. 4), which is provided for the purpose of engaging the roller 147 on the arm 55 of the selector slide 54 and thus returning the selector to its original position; this return operation may be at the completion of a printing operation or whenever the error key 21 of the keyboard A is actuated.

In the operation of the clearing device by key 21, upon the depression of that key, a keyboard clutch associated with it is operated; this operates of the key bars 149 of the key bar bank B, which engages the rocking arm 150 (Fig. 7), on a shaft 151; a rocking arm 152 on shaft 151 is connected to a link member 153 which is attached to and operates the rock shaft 136.

In the form of parcel post machine illustrated it is required that six keys be operated in the keyboard A to set up six numerals in the numeral printer; to actuate the selector C to progressively move to six different positions, I have provided a progressive release lock S which controls the power clutch K, so that the shaft L cannot be operated to connect for a printing operation unless the set-up has been properly made; for illustration, if six key depressions (of the same or different keys) have been made, the progressive release lock has rotated to a point where it will have removed its locking means from the clutch member, and the clutch may be operated; if only five keys have been punched in, the locking element will not be removed; if seven keys are punched in the locking element will have been removed at the operation of the sixth key, but, upon the depression of the seventh key, will return into locking position; to effect these various movements I have provided a simple but effective mechanism in the progressive release lock which I will now briefly describe, and which is fully disclosed in a co-pending application filed October 23, 1931 Serial No. 570,631.

The main actuating element of the progressive release lock is the ratchet wheel 154 secured to a shaft 155; wheel 154 has on its periphery a set of 14 teeth 156 and on one of its faces two pins 157 and 158; actuation of wheel 154 is effected by a spring-tensioned pawl 159 rockably mounted on a pin 160 in a rocking arm 161 rockably mounted on the shaft 155 and rocked by a link arm 162; arm 162 is connected by link 163 (Fig. 7), to a rock arm 164 secured to the shaft 155, to which is also secured a butterfly 166; all of the key bars of the bank B except the error key bar 149 bear against the butterfly 166 when they are depressed for setting up a number in the machine; the butterfly 166 has a recess 167a (Fig. 11), which permits the key bar 149 to be operated without contacting the butterfly 166.

At each operation of a key bar for setting up a numeral, the ratchet wheel 154 is rotated one tooth width and the operation is as follows: 70 referring, for example to the pin 157 (Fig. 1), upon the performance of five key-actuations and the consequent rotation of the wheel 154 a distance equal to five teeth thereof, the pin 157 has rotated to the point at which it con- 75

tacts the end of the lock bar 167; upon the occurrence of the sixth key actuation in the keyboard the pin 157, by its further movement moves the lock bar 167 and its connected lock 5 168 actuates the bell crank lever 169 and the latch 170 which normally engages the latch pin 171 of the power clutch K.

Upon the operation of the clearing mechanism to clear the machine the rack bar 145 is moved 10 longitudinally thereby operating the pinion 172 which is in engagement with the rack of the rack bar; rotation of pinion 172 rotates a driving member 173, these members being connected and rotatably mounted on shaft 155; pawls 174 15 in driving member 173 (Fig. 5), are adapted to engage internal teeth 175 in a driven member 176; this driven member is secured to the shaft 155 and, upon being rotated, rotates the shaft 155 and the ratchet wheel 154 thereon; 20 the driven member 176 is provided with a spring brake 177 adapted to engage in dwells 178 for final positioning of that member.

The clearing operation, in so far as it relates 25 to the progressive release lock, consists in the actuation of the pinion 172 and the consequent rotation of the driving member 173 and pawls 174 within the driven member 176; the pawls engage the teeth 175 at whatever position they may happen to occupy picking up the driven 30 member 176 and rotating it to its original position, thus re-setting the pins 157 and 158 to normal position; when the pins are so re-set the lock bar 167 is at its original position and the lock 168 is out of engagement with the 35 spring-tensioned bell crank 169, which positions itself to engage the latch 170 with the pin 171; for the purpose of preventing reverse action of the ratchet wheel 154 I have provided a spring-tensioned pawl 179.

40 To comply with the requirements for a machine of this character, it is necessary that there be provided a meter which can be set for a predetermined amount of postage, and which, upon the exhaustion of the pre-set 45 amount, will operate to lock the machine against further operation until it is re-set by an authorized person; to that end I have provided the control meter P, which includes mechanism by which such locking re-setting actions may be 50 performed.

The meter wheel 180 of the train of meter wheels in the control meter P (Fig. 1) is provided on one side with a cam face 181 designed to contact, upon rotation of wheel 180 with 55 a spring-tensioned trip lever 182; normally positioned in the path of the cam 181; trip lever 182 has a foot 183 (Fig. 5), which extends beneath the drive bar 184 and which, when set, retains this drive bar in an elevated position; 60 when the cam 181 contacts the trip 182 the latter is moved outwardly, carrying its foot 183 from beneath the drive bar 184 which thereupon drops down, this movement being permitted by the slotted opening 185 in which the guide pin 65 186 is positioned; the descent of the drive bar 184 brings the latch 187 into the path of the cam 188 secured to the shaft 181.

The locking operation occurs at the completion 70 of a printing operation, to permit the last stamp printed to be issued. At the completion of a printing operation, when the locking operation is to occur, the shaft 181 is actuated and the cam 188 is thereby operated to pick up the latch 187 and move the drive bar 184 a predetermined distance to actuate a mechanical lock 75

and an electric switch. The mechanical lock consists of a pawl 189, operating against a ratchet wheel 190 secured to the drive shaft L (Fig. 1) the electrical switch V (Fig. 2) is of the conventional quick-throw type and operates to disconnect the motor circuit when the lock mechanism, including the drive bar 184, is operated by the control meter P.

These locks are released, upon the re-setting of the control meter, by means of a key lock 191 through its connections 192 with a rock shaft 193, to one end of which is secured a cam lever 194 (Figs. 1 and 5); this lever lifts the drive bar 184 out of contact with the cam 188, whereupon it is returned longitudinally by spring 184a to original position and is held in its elevated position by the lever 194 until the meter is re-set; during the re-setting operation the cam 181 is removed from contact with the trip 182, thus allowing the trip foot 183 to return 20 beneath the drive bar 184 and hold it in its normal elevated position after the removal of the lever 194 by the locking of the control meter P and the removal of the key from the lock 25 191; when the meter and the meter control lock have thus been returned to original position they are ready to be operated for another locking operation. The return movement of the drive bar 184 to its original position releases the pawl and ratchet lock 189—190 (Fig. 1) and operates 30 the switch V (Fig. 2) to close the motor circuit, thus placing the machine in operable condition. This mechanism is fully disclosed in a co-pending application filed October 23, 1931, Serial No. 570,634.

35 For the purpose of providing power for the printing operation and its related movements, I have provided the power clutch K which is of the conventional pin-clutch type, wherein driving and driven members of the clutch are engaged and disengaged at predetermined points of revolution. The operation of this clutch is controlled in part by the engagement and disengagement of latch 170 with latch pin 171 in accordance with the operation of the set-up 40 mechanism, a part of which has been hereinbefore described.

45 For operation of the power clutch K I have provided the manual control key 22 on the keyboard A, which, by means of the link 195 and the 50 pivotally connected members 195a, 195b and 195c, actuates a trip member 196, which is normally in engagement with the latch pin 171, of the clutch K. The clutch may be engaged, by operation of the control key 22, provided that 55 the proper set-up has been made by means of actuation of the keys of the keyboard A, so that the latch 170 will have been disengaged from the pin 171; when the clutch is disengaged it remains in disengaged position until it is again 60 manually operated by means of the control key 22. This mechanism is the subject of a co-pending application filed October 23, 1931, Serial No. 570,636.

The parcel post machine herein disclosed is 65 adapted to print stamps upon a paper tape and duplicate stamps upon a duplicate tape; for the purpose of printing the stamp form upon the paper tape preparatory to the printing of the numerals which complete the stamp, I have 70 provided a rotary printer M which comprises a conventional drum printer with a rotary platen, the indicia plate of which is so disposed upon the periphery of the drum that it will contact the paper against the platen roller at the 75

printing zone at the time that the paper tape is being moved forward, after the printing operation of the numeral printer.

To provide for an intermittent operation of the conveying elements for the paper tapes, I have provided an intermittent clutch N, and appropriate connections with the shaft L and the printing and conveying mechanism. This particular unit has no direct bearing upon the subject of this invention, beyond the fact that, through its control, the paper tapes are fed intermittently through the numeral printer and the ink ribbon is properly fed beneath numeral printer E by the ribbon feed and reversing mechanism 100. This intermittent clutch mechanism is the subject of a co-pending application, filed October 23, 1931, Serial No. 570,630.

Upon the completion of a printing operation, during which the numeral printer has printed the numerals upon a stamp length of the paper tapes, both tapes are forwarded by the conveying mechanism, the original stamp traveling into a discharge and moistening element U; upon the completion of the forwarding movement of the stamp length a knife element 199 (Fig. 2) severs the completely printed stamp from the balance of the paper tape, and by manipulation of the handle 203, the stamp may be deposited upon the delivery plate 204, properly moistened and ready to be attached to a parcel. This moistening unit U is the subject of a co-pending application, filed October 23, 1931 Serial No. 570,626.

The duplicate tape is wound upon a spindle, (not shown), the handle 292 of which, (Fig. 2) furnishes means by which the duplicate paper tape may be removed from the machine.

The type-setting mechanism herein disclosed includes several cooperating elements, namely, the keyboard unit A, the key bar bank B, the selector unit C, the rack bar bank D, the numeral printer E, and the meter set-up mechanism G.

In the operation of setting up a number on one of the type bearing numeral wheels in the numeral printer E, the actuation of one of the keys 20 connects the power supply from the drive shaft 25, through the eccentric 27 and the eccentric ring 28 to the key bar bank B; this connection is accomplished by depressing one of the keys 20 and its connected key stem 31, thereby rocking the trip bar 32, which disengages the trip 33 from the latch 34, thus allowing engagement of the tooth 39 with one of the teeth of the toothed clutch element 26, thus effecting engagement of the clutch (Fig. 8); while the clutch is engaged the latch 34 and its attached elements make one complete rotation; prior to the completion of this rotation the arms 42 and 44 under the influence of cam face 48 of cam 37, rock the trip bar 32 and restore the trip 33 to its position in the path of the latch 34; upon the completion of the rotation the trip 33 again engages the latch 34 removing the tooth 39 from engagement with the toothed element 26 and thus releasing the clutch.

The movement originating in the depression of one of the keys 20 and transmitted through this clutch follows through the particular one of the key bars B associated with the actuated key to the bell cranks 47 (Fig. 11) connected to the key bar and to one of the push rods 48.

The bell cranks 47 are of different ratios of leverage, providing differential movements of

rods 48 corresponding to the numerical marking of each key, for the purpose of providing a mechanical set-up equivalent to the numbers punched in on the keyboard; the particular movement desired and achieved in this mechanism is to rotate the type-bearing numeral wheels in the numeral printer with such relation to the keys on the keyboard that when a key bearing, for example, the numeral 1, is depressed, the corresponding push bar 48, by means of the corresponding bell crank 47, will be actuated only a distance sufficient to rotate the particular type wheel being operated upon to bring the type face bearing the numeral 1 to the printing position.

As a further illustration, if the key on the keyboard bearing the numeral 3 is depressed, the actuation will move the corresponding bell crank 47, with its predetermined ratio of leverage, to actuate the corresponding push bar 48 a distance sufficient to transmit into the numeral printer wheel a degree of rotation sufficient to bring the type face bearing the numeral 3 to the printing position.

The parcel post machine herein disclosed is designed to operate to set up six different numeral wheels in the numeral printer by means of a single key bank of ten keys on the keyboard A; since there must be six different and complete operations of setting up individual numerals upon six different numeral wheels in the numeral printer E, I have provided an intermediate mechanism disposed between the keyboard mechanism, the numeral printer E, and the connected meter set-up mechanism G, wherein the movements originating in the keyboard and transmitted as differential movements by the push bars 48 are applied selectively and in succession to the rack bars for the respective numeral wheels; this intermediate mechanism comprises the selector unit C.

In this selector unit I have provided a means for progressively contacting individually each of the bars comprising the bank of rack bars D, which are geared directly to the respective numeral wheels in the printer E. In Figs. 12, 13, 14, 15 and 16 are illustrated the series of movements of the various parts of the selector unit.

In Fig. 12 the selector is shown in side elevation, partly in section, from the front of the parcel post machine; the carriage 51 is shown in solid lines in normal position, and in broken lines at the extreme limit of its longitudinal movement, equal to the distance traveled when the ninth key is punched on the keyboard A; this figure also illustrates the two extreme positions of the selector arm 57.

Fig. 13 illustrates the two extreme positions of the selector slide 54, the solid lines showing its original or starting position, with the selector arm 57 positioned opposite the first rack bar 233, which is the rack bar connecting and operating the numeral wheel bearing the figures indicating the zone to which the package to be stamped is to be sent. The position shown in broken lines in Fig. 13 shows the extreme movement of the slide 54 transversely of the carriage 51; in this position the selector arm 57 is positioned opposite the rack bar 107, which is connected to and operates the numeral wheel in the numeral printer E bearing figures indicating the number of cents of the monetary value of the stamp.

Fig. 13 also indicates the escapement operation of the selector slide 54, which is provided

on its lower surface with the teeth 58; upon the longitudinal movement of the carriage 51 (to the left in Fig. 1), the particular tooth engaged by the pawl 59 slides upon the guide plate 60, disengaging the tooth from pawl 59; upon such disengagement the pawl 59, under tension of the spring 59a, rocks into the dotted position shown at 207, where it is so disposed that it will engage the next adjacent tooth upon the return 10 of the carriage 51 to its starting position; the tooth previously engaged, which was riding upon the guide 60, and which is now returned to its original position, finds no support, in the form of the pawl 59 which previously blocked its 15 path, and the slide 54, under tension of the spring 56, moves longitudinally (to the left in Fig. 13), whereupon the next succeeding tooth engages the pawl 59 at its position 207 and forces it back until it rests against a stop 208; 20 the selector slide, together with its selector arm, is thus positioned for the next succeeding operation.

Assuming that the operation just described was the first in the setting up of a series of numerals for stamp printing purposes, the selector has now moved to the second tooth and the selector arm 57 is positioned directly opposite the rack bar 204, which contacts with, and operates, the numeral wheel in the numeral printer E bearing the type faces for printing the tens of pounds upon the stamp; upon the actuation of another key in the keyboard A the selector repeats the operation just described, the escapement movement occurs, and the selector 35 arm 57 is positioned opposite the rack bar 205, which contacts with and actuates the numeral wheel in the numeral printer E bearing the type faces for printing the units of pounds upon the completed stamp. Repetition of this operation 40 successively presents the selector arm 57 to each of the rack bars 105, 106 and 107; these three bars actuate numeral wheels bearing the type faces which indicate respectively the dollars, tens of cents and cents comprising the monetary 45 value of the stamp being printed.

Fig. 14 diagrammatically illustrates in solid lines the selector unit in its normal starting position, and in broken lines the position the carriage 51, carrying the selector slide 54, assumes upon the actuation of the keyboard key bearing the numeral 1. This operation actuates the push bar 209 of the bank 48; bar 209, by means of its bell crank lever 47 is so disposed as to move only a distance sufficient to move the selector arm 57 the distance required to rotate the actuated numeral wheel of the printer E, to bring the type face bearing the numeral 1 into printing position.

Fig. 15 illustrates the selector arm 57, together 60 with the selector slide 54, as actuated a sufficient number of times to place the arm in position opposite the rack bar 105; this particular rack bar acts to set up the numeral wheel for the dollars figure of the monetary value to be 65 printed; upon actuation of the key bearing the numeral 5 the push rod 210 is moved a distance sufficient to move the selector arm and the rack bar 105 to rotate the dollars numeral wheel to bring the type face bearing the numeral 5 into 70 printing position.

Fig. 16 illustrates the final position of the selector slide 54 and the selector arm 57; the selector arm 57 is positioned opposite the last rack bar 107 in the group 107, which bar actuates 75 the cents numeral wheel of the printer; the

broken lines show the limit of the movement of the selector carriage 51, together with its supported selector slide 54 and selector arm 57. Assuming that the keyboard key bearing the numeral 9 has been actuated, the push bar 211 will have been moved a distance sufficient to actuate the other movable members to a point where the numeral wheel for printing the cents figure on a stamp will have been rotated to present the type face bearing the numeral 9 10 to the printing zone.

By the use of my invention each of a plurality of type wheels (for example, six) is successively rotated to present to the printing zone a figure corresponding to any one of the figures 0 to 9 15 on a selectively actuated key of a single keyboard of ten keys. This operation is ordinarily performed by means of a multiple keyboard of sixty keys, comprising a complete bank of keys from 0 to 9 for each type wheel.

In the operation of this keyboard the operator must perform six key-actuations (of the same or different keys) before the machine is operable for printing purposes; the selector used necessitates that it be successively moved through the 25 six steps of the escapement mechanism in order to position it successively opposite each of the rack bars of the rack bar bank D so that it may actuate each of the numeral wheels in the numeral printer E; however, should a printer be required having any greater or less number of numeral wheels, the same operation, including the same principle, could be used, by slight modification of the structure.

The rack bars D actuated by the selector arm 35 57 require means to retain them in their actuated positions until after a printing operation has been completed; to that end I have provided the ratchet teeth 97, which are contacted and retained in set position by spring-tensioned 40 pawls 95 rockably mounted on the sliding shaft 96.

For the purpose of maintaining the operated relation between the rack bars D and the numeral wheels 62 of the numeral printer, I have 45 provided means (racks 93 and pinions 94) for rotating the numeral wheels and a locking member 68 (a portion of the hammer 66) to engage the particular type member of the numeral wheels 62 which is opposite the printing opening at the time the printing operation is instituted; this engagement maintains the numeral wheels and their pinions in their set-up condition relative to the racks. The parts continue in this relation during the printing operation, and until after the numeral wheels have 50 returned upwardly from their printing operation and the pinions 94 again engage the racks 93, at which time the hammer 66 is raised a sufficient distance to insure that the locking member 68 is disengaged from the numeral wheel 62. 55

The locking operation of the ratchet pawls 95 (Fig. 9) just described is necessary in view of the fact that the rack bars 105, 106 and 107, which constitute the monetary value group, are employed for transmitting the movement originating in the keyboard A to the meter set-up mechanism G; this operation is effected by engagement of bar 87 with the rack bar extensions 108 (Fig. 17) and the movement is carried therefrom through the gearing 111 and connecting elements F. The elevators 113, 114 and 115, of the mechanism G are moved to set up the mechanical equivalents of the numerals manually set up on the keyboard A; these mechanical 75

equivalent numbers are maintained in the meter set-up mechanism until the latter mechanism is actuated during a printing operation for transmission of the set-up into the control meter P and the total meter R.

At the completion of a printing operation the clearing action takes place within the machine automatically by means of the cam 149 and the cam arm 139 and its connected parts, namely, the rock shaft 137 and the rock shaft 136. The rock shaft 137, by means of the cam 141, slides the slide shaft 96 laterally which laterally displaces the pawls 95 from their contact with the ratchet teeth 97 on the rack bars D, allowing the spring-tension rack bars D to return to their original position; should any of the rack bars fail to return by spring tension, they are returned by a power return element, comprising the bar 87 mounted in the rocking arms 88 (Fig. 17), which engages the rack bar extensions 108 and returns the bars to their original positions. This same clearing action operates the rocking arm 146 on shaft 136 (Fig. 4), which engages the pin 147 on the selector slide 54, and returns the selector slide to its original position (shown in Figs. 4 and 13), for the next set-up operation.

While the form of mechanism here shown and described is admirably adapted to fulfill the objects primarily stated, it is to be understood that it is not intended to confine the invention to the one form of embodiment herein disclosed, for it is susceptible of embodiment in various forms, all coming within the scope of the claims which follow.

I claim:

1. In a device of the character disclosed, a printer comprising rotatable numeral printing wheels normally maintained in a zero position; a selector device having a definite number of operative positions, said selector successively rotating said numeral wheels from a zero position to a numerical combination position; a keyboard mechanism adapted to be manipulated a definite number of times to actuate said selector device to the said definite number of positions, and a progressive release lock controlling the printing operations of said printer, said progressive release lock adapted to be actuated to a lock releasing position upon a predetermined definite number of manipulations of said keyboard.

2. In a device of the character disclosed, a printer comprising rotatable numeral printing wheels normally maintained in a zero position; a selector device for successively rotating said numeral wheels from a zero position to a numerical combination position; a keyboard mechanism having keys and keybars and adapted to actuate said selector device, power means to operate said printer for printing purposes, locking means preventing operation of said printer, and lock-releasing means actuated by a predetermined number of actuations of said keys and keybars to lock releasing position to permit the power-operation of said printer when said keyboard has been manipulated a predetermined number of times.

3. In a parcel post machine, a printer comprising rotatable numeral printing wheels normally maintained in a zero position; a selector device for successively rotating said numeral wheels from a zero position to a numerical combination position; said selector having a normal rest position; a keyboard mechanism adapted to actuate said selector device; a progressive re-

lease lock normally in locking position and adapted to be actuated to a lock releasing position upon a predetermined number of manipulations of said keyboard; key elements in said keyboard mechanism; and clearing mechanism adapted to be operated by one of said key elements to simultaneously return said numeral wheels to their zero position, said selector to its normal rest position, and said progressive release lock to its locking position, for the purpose or preparing the machine for the next set-up operation.

4. In a device of the character disclosed, a selector element comprising a carriage adapted to be moved laterally in its own path by actuation of a keyboard element, a selector slide carried by said carriage and adapted to move laterally in its own length in a direction transverse to the movement of the carriage; said slide having an escapement element providing stepped movement of the slide, and means to permit said slide to escape one step for each actuation of said carriage by said keyboard.

5. In a device of the character disclosed, a selector element comprising a carriage adapted to be moved laterally in its own path by actuation of a keyboard element, a selector slide carried by said carriage and adapted to move laterally in its own length in a direction transverse to the movement of the carriage; said slide having an escapement element providing stepped movement of the slide; means to permit said slide to escape one step for each actuation of said carriage by said keyboard; and means to actuate the said carriage from said keyboard to permit the escapement movement of said slide.

6. In a device of the character described, a keyboard mechanism having keys, a printer comprising printing wheels, a selector device actuated by said keyboard mechanism to move to a plurality of positions successively, and to rotate said printing wheels successively to positions corresponding to the successive actuation of keys on said keyboard, locking means preventing printing operations of said printer, and means for releasing said locking means to permit said printing operations upon a predetermined number of actuations of said keys.

7. In a device of the character described, a keyboard mechanism having keys, a printer comprising printing wheels, a plurality of movable setting members actuated by said keys, a plurality of transfer members for rotating said printing wheels, and a selector device actuated by said setting members and movable to a plurality of positions successively, said selector device having means for engaging said transfer members successively and upon actuation by said setting members moving said transfer members successively to move said printing wheels to positions corresponding to the successive actuation of keys of said keyboard mechanism.

8. In a device of the character described, a keyboard mechanism having keys, a printer comprising printing wheels, a plurality of movable setting members actuated by said keys, a plurality of transfer members for rotating said printing wheels, and a selector device actuated by said setting members and movable to a plurality of positions successively, said selector device having means for engaging said transfer members successively and upon actuation by said setting members moving said transfer members and said printing wheels to positions correspond-

- ing to the successive actuation of keys of said keyboard mechanism, locking means preventing printing operations of said printer and means for releasing said locking means to permit said printing operations upon a predetermined number of actuations of said keys.
9. In a device of the character described, a keyboard mechanism having keys, a printer comprising printing wheels, a selector device actuated by said keyboard mechanism to move to a plurality of positions successively and to rotate said printing wheels successively to positions corresponding to the successive actuation of keys of said keyboard mechanism, locking means preventing printing operations of said printer, means for releasing said locking means to permit said printing operations upon a predetermined number of actuations of said keys, printer-operating means for preventing rotation of said printing wheels and simultaneously moving said printing wheels to printing position, and means for releasing and clearing said printing wheels upon the completion of said printing operation.
10. In a device of the character described, a keyboard mechanism having keys and keybars, a printer comprising printing wheels, a plurality of differential setting members each connected to and actuated by the respective keybars, a plurality of transfer racks engaging said printing wheels for rotating said wheels, a selector device engageable by said setting members and movable thereby toward said transfer racks, said selector device being movable transversely of said setting members and said transfer racks to a plurality of positions successively, said selector device having a selector member thereon positioned by said transverse movement to engage said transfer racks successively and when moved by said setting members actuating said transfer racks successively to move said printing wheels to positions corresponding to the successive actuation of keys of said keyboard.
11. In a device of the character described, a keyboard mechanism having keys and keybars, a printer comprising printing wheels, a plurality of differential setting members each connected to and actuated by the respective keybars, a plurality of transfer racks engaging said printing wheels for rotating said wheels, a selector device engageable by said setting members and movable thereby toward said transfer racks, escapement means for moving said selector device transversely of said setting members and said transfer racks to a plurality of positions successively, said selector device having a selector member thereon positioned by said transverse movement to engage said transfer racks successively and when moved by said setting members actuating said transfer racks successively to rotate said printing wheels to positions corresponding to the successive actuation of keys of said keyboard mechanism, printer-operating means for moving said printing wheels out of engagement with said transfer racks and into printing position and simultaneously preventing rotation of said printing wheels, latch means for retaining said transfer racks in set-up condition, and means for releasing and restoring said printing wheels to engagement with said transfer racks and for releasing said latch means and clearing said printing wheels upon the completion of a printing operation.
12. In a device of the character described, a printer comprising numeral printing wheels normally maintained in a zero position, a selector device, keyboard mechanism having keys and keybars adapted to operate said selector device for successively rotating said numeral wheels from a zero position to a numerical combination position corresponding to the numerical combination represented by the keys actuated, power printing means for locking said printing wheels against rotation and simultaneously operating said printing wheels to perform a printing operation, power-locking means preventing the operation of said power printing means, means for releasing said power-locking means upon performance of a predetermined number of actuations of said keys and keybars and power driven means for returning said printing wheels to their zero position upon completion of a printing operation of said printer.
13. In a device of the character described, a keyboard mechanism having keys and key bars, a printer comprising printing wheels, a plurality of transfer members independent of said key bars for rotating said printing wheels, and a selector device differentially actuated by said key bars, said selector device having means for engaging said transfer members successively and upon actuation of said selector by said key bars moving said transfer members successively to rotate said printing wheels differentially to positions corresponding to the successive actuation of keys of said keyboard mechanism.
14. In a device of the character described, a keyboard mechanism having keys and key bars, a printer comprising printing wheels, a plurality of movable transfer members for engaging and rotating said printing wheels, a selector device differentially movable by said key bars, said selector device having means thereon relatively movable to a plurality of positions to engage said transfer members in succession, said relatively movable engaging means being moved by the key actuated movement of said selector device to move said transfer members successively and differentially in accordance with the actuation of said keys.
15. In a device of the character described, a selector element comprising a carriage adapted to be moved by actuation of a keyboard element, a selector slide carried by said carriage and movable relative to said carriage to successive predetermined positions relative thereto, and escapement means providing step by step movement of said slide to said positions.
16. In a device of the character described, a keyboard mechanism having keys, type wheels, transfer members for engaging and operating said type wheels, selector means for transmitting to said members in succession the differential movements of said key actuated means, said selector means comprising a movable carriage and a slide relatively movable thereon successively to predetermined positions adjacent each of said members in succession, and means associated with said key bars for moving said carriage and slide differentially to transmit differential movement successively to said members and type wheels.
